INVENTOR.

UNITED STATES PATENT OFFICE.

WALTER BRENT CLARK, OF CHICAGO, ILLINOIS.

DESIGN FOR A GAME-BOARD.

No. 39,306.

Specification for Design.

Patented May 12, 1908.

Application filed November 30, 1906. Serial No. 345,842. Term of patent 3½ years.

To all whom it may concern:

Be it known that I, WALTER BRENT CLARK, a citizen of the United States, residing at Chicago, in the county of Cook and State of Illinois, have invented a new, original, and ornamental Design for a Game-Board, of which the following is a specification, reference being had to the accompanying drawing, forming part thereof.

The figure of the drawing is a plan view of the game board showing the design.

I claim:

The ornamental design for a game-board, as shown.

WALTER BRENT CLARK.
